ELECTRICAL OUTLET SAFETY CAP

Elliot H. Hartford, 1048 Ramapo Valley Road,
Mahwah, N.J. 07430

Filed July 27, 1970, Ser. No. 24,155

Term of patent 14 years

Int. Cl. D8—99; D13—99
U.S. Cl. D26—1

FIG. 1

FIG. 2

FIG. 3

FIG. 4

FIG. 5

FIG. 6

FIG. 1 is a front perspective view of the electrical outlet safety cap showing my new design;

FIG. 2 is a rear perspective view of the electrical outlet safety cap of FIG. 1;

FIG. 3 is a front elevation view of the electrical outlet safety cap of FIG. 1;

FIG. 4 is a rear elevation view of the electrical outlet safety cap of FIG. 1;

FIG. 5 is a side elevation view of the electrical outlet safety cap of FIG. 1; and

FIG. 6 is a plan elevation view of the electrical outlet safety cap of FIG. 1.

I claim:

The ornamental design for an electrical outlet safety cap, as shown.
